ABRAM N. PASMAN, OF WATERBURY, CONNECTICUT.

FLUSH-VALVE.

1,300,001.

Specification of Letters Patent.

Patented Apr. 8, 1919.

Application filed July 13, 1918. Serial No. 244,727.

To all whom it may concern:

Be it known that I, ABRAM N. PASMAN, a citizen of the United States, residing at Waterbury, in the county of New Haven and 5 State of Connecticut, have invented an Improvement in Flush-Valves, of which the following is a specification.

This invention relates to a flush valve and more particularly to that type of flush valve 10 shown and described in Letters Patent No. 1,225,352, granted May 8th, 1917. In this type of flush valve, the valve upon being opened, is maintained in an open position by the pressure of the medium flowing 15 through the body portion of the valve and acting against vanes provided therein until the pressure is reduced to such an extent as to permit the valve to drop by gravity and close.

20 The novel feature of the present invention is the provision of a device associated and coacting with the vane or vanes employed in such a manner as to control the flow of the medium through the body portion of 25 the valve to cause a uniform movement thereof in closing, so that a sudden closing of the valve when the pressure is reduced to a predetermined extent, is obviated. This at the same time may be of different proportions so as to control within predetermined 30 limits the pressure at which the valve will close.

The construction comprising my present invention will be hereinafter more particularly described, in conjunction with the accompanying drawings, in which

35 Figure 1 is a central cross section and partial elevation illustrating a flush tank fitted with a valve made in accordance with this 40 invention, showing the valve in a closed position.

Fig. 2 is a central longitudinal cross section of the valve and parts associated therewith, showing the same in an open position.

45 Fig. 3 is an inverted plan view of the parts shown in Fig. 2.

Fig. 4 is an elevation of the parts of the valve showing the same still further enlarged and in the closed position, and

50 Fig. 5 is an inverted plan view of the parts of the valve as shown in Fig. 4.

Referring to the drawing, 10 indicates a tank which as is customary in such devices, is provided with a pipe fitting preferably 55 comprising a flange 11, a tubular stem or body portion 12 extending upwardly there-

from and also a tubular stem or body portion 13 extending in the opposite direction. The tubular stem 13 is exteriorly screw-threaded and passed through an opening 60 provided therefor in the bottom wall of the tank 10. This fitting is secured in position in the tank by a nut 14, which is turned down on the tubular stem 13 so as to abut 65 against the under face of the tank. Connected to and extending from the pipe fitting is a flush pipe 15, the connection being made by a nipple 16 or otherwise, as clearly indicated in Fig. 1 of the drawing. This flush pipe 15, as will be understood, runs to a 70 closet or other place in which the water from the tank is used for flushing purposes.

The valve comprising the present invention preferably includes a ring member indicated at 17 and having a flange 18. A 75 washer or valve of rubber or other material is indicated at 19 and is fitted over the ring 17 and is of sufficient diameter to extend appreciably beyond the flange 18. In this form of the invention I also employ an annular head 20 having a flange 21 thereon and adapted to lie against the washer or valve 19 so that the same is secured in position between this flange 21 and the flange 18. These parts are secured in position by the 80 overflow pipe 22, the inner end of which is adapted to be turned to place in the ring 17.

In spaced positions in the flange 18 there are bosses 23, suitably secured to which are blades 24, 25, 26. These blades assume 90 equally spaced positions, and being three in number, are placed at 120° apart. Furthermore these blades are of such an extent as to fit and to be movable within the tubular body portion 12 of the pipe fitting, one of 95 the functions of the blades being to guide the valve in the movements thereof. To the blade 25 there is pivotally connected a vane 27, the wings of which are indicated at 28, 29. These wings 28 and 29 of the vane 27 100 preferably assume the same angle as that between the blades 25, 26, so that the wing 28 lies against the blade 25 and when the valve is open the wing 29 lies against the blade 26. The vane 27 is pivotally connected to the 105 blade 25 as indicated at 30 and adjacent the pivotal point extends sufficiently far to permit the end 29' of the wing 28 to engage with the extremity of the tubular body portion of the fitting to maintain the valve in an 110 open position, as hereinafter more particularly described. At the lower or opposite

end of the vane the wings 28, 29, thereof are recessed as indicated at 31.

Associated with the parts hereinbefore described, I also employ a cup member 32. 5 This is connected with a lever 33, and as illustrated, may be an integral part thereof. The lever 33 terminates in a rib 34 which is an integral extension on the under surface of the cup 32. The lever 33 is provided with 10 a boss 35 adapted to bear against the face of the blade 25 and through the lever and boss and the blade 25, a pivot 36 is passed upon which the lever and the cup are adapted to swing. The lever 33 is so mounted that 15 the free end thereof extends through the recess in the lower or inner ends of the wings 28, 29, of the vane 27, and the blade 29 is provided with a lug 37 against which one edge of the lever 33 is adapted to contact in 20 the operation of the valve. Furthermore, it will be noted, that as clearly illustrated in Figs. 4 and 5, the lower end of the wing 28 as indicated at 38 lies between the lower portion of the blade 25 and the lever 33 and is 25 adapted to bear against the boss 35 for a purpose which will be hereinafter explained.

The hereinbefore described apparatus may be operated by any suitable mechanism, for instance as illustrated in Fig. 1, by a lever 30 39 adapted at one end to engage in a slot in the overflow pipe 22 and pivotally mounted at 40 adjacent its opposite end in the bracket 41 secured to the tank 10. Secured to the opposite end of the lever 39 is one end of a 35 pull-chain 42 and in suitably placed positions the overflow pipe may be provided with one or more apertures 43 through which when the water in the tank reaches the same, the water will overflow through 40 this pipe.

The wing 29 as clearly illustrated in Fig. 4, may be provided with bosses 28' which when the vane is in the dotted position, prevent the wing 29 from contacting in its entire surface with the blade 26 so as to insure the proper action of the vane by preventing its adhesion to the blade 26 by any means whatsoever.

In the operation of this apparatus the 50 parts of the valve normally assume the positions shown in Figs. 1, 4 and 5. While the valve is held in its normally seated position against the upper edge of the tubular body portion 12 of the pipe fitting, the parts of the valve are held in this position in the tubular body member by the end 29' of the wing 28 bearing against the inner surface of the tubular body member 12. But when the valve is raised from its closed position, 55 as shown in Fig. 1, to its open position as shown in Fig. 2, in which the washer or valve 19 leaves its seat on the upper or outer end of the tubular body member 12, the water or other medium in the tank will be 60 permitted to flow through the tubular body 65

member to the flush pipe 15 and the pressure of the water acting against the wing 29 forces the vane from the position shown in full lines Fig. 4, to that shown in dotted lines therein. In this action as will be understood, the cup 32 will also descend from the full line position, Fig. 4, to the dotted line position, this action being caused by the action of the water against the cup and being assured by the end 38 acting against the boss 35. In this position, the end 29' of the wing 28 extends beyond the upper end of the tubular body member 12, and so long as the pressure against the cup 32 and the wing 28 is sufficient to maintain these parts in these positions, the valve will remain open. After the pressure decreases, however, the vane 27 will gradually swing to the full line position as shown in Fig. 4, and in so doing, will gradually swing the lever 33 so as to raise the cup 32 by the action of the lug 37 against the edges of the lever 33. In so doing as will now be understood, the water pressure against the cup is not only reduced but the water remaining in the cup, permitted to flow therefrom as the same is tilted. In this manner the sudden seating of the valve is prevented, and dependent upon the size and inclination of the cup, the pressure at which the valve is closed may be controlled within 95 predetermined limits.

I claim as my invention:

1. A flush valve apparatus comprising a tubular body member having a seat thereon, a valve member adapted to bear against said seat, a vane movably connected to said valve member, and a device also movably connected to said valve member and coacting with said vane so that the pressure exerted against the vane and said device by a medium flowing through said tubular body member causes a part of said vane to bear against said tubular body member to maintain the valve in an open position.

2. A flush valve apparatus comprising a tubular body member having a seat thereon, a valve member adapted to bear against said seat, a vane pivotally connected to said valve member, and a device also pivotally connected to said valve member and coacting with the said vane so that the pressure exerted against the said device and vane by a medium flowing through said tubular body member causes a part of the said vane to bear against the said tubular body member to maintain the valve in an open position.

3. A flush valve apparatus comprising a tubular body member having a seat thereon, a valve member adapted to bear against said seat, a vane movably connected to said valve member, and a cup member also movably connected to said valve member and coacting with said vane so that the pressure exerted against the vane and said cup member by a medium flowing through said tubular body

member causes a part of said vane to bear against said tubular body member to maintain the valve in an open position.

4. A flush valve apparatus comprising a tubular body member having a seat thereon, a valve member adapted to bear against said seat, a vane pivotally connected to the said valve member, and a cup member also pivotally connected to said valve member and 10 coacting with the said vane so that the pressure exerted against the said cup member and vane by a medium flowing through said tubular body member causes a part of the said vane to bear against the said tubular body member to maintain the valve in an 15 open position.

5. A flush valve apparatus comprising a tubular body member having a seat at the end thereof, a valve adapted to bear against 20 said seat, a plurality of angularly placed blades movably fitting within said tubular body member and connected to the said valve, a vane pivotally connected to one of the said blades, and a device also pivotally 25 connected to one of the said blades and associated and coacting with the said vane so that the pressure exerted against the said device and vane by a medium flowing through the said body member causes a part of the said 30 vane to bear against a portion of the said tubular body member to maintain the valve in an open position.

6. A flush valve apparatus comprising a tubular body member having a seat at the 35 end thereof, a valve adapted to bear against said seat, a plurality of angularly placed blades movably fitting within said tubular body member and connected to the said valve, a vane pivotally connected to one of the said blades, and a cup member also pivotally 40 connected to one of the said blades and associated and coacting with the said vane so that the pressure exerted against the said cup member and vane by a medium 45 flowing through the said body member causes a part of the said vane to bear against a portion of the said tubular body member to maintain the valve in an open position.

7. A flush valve apparatus comprising a 50 tubular body member having a seat at the

end thereof, a valve adapted to bear against the said seat, a plurality of angularly placed blades secured to the said valve and fitting movably within the said tubular body member, an angular vane having wings placed 55 at the same angle as the angle between the said blades, one of the said wings being pivotally connected to one of the said blades, a lever also pivotally connected to the said blade, and a device associated with the 60 said lever and actuated thereby through the said vane, so that the pressure exerted by a medium flowing through the said body member causes a part of the said vane to bear against a portion of the said tubular body 65 member to maintain the valve in an open position.

8. A flush valve apparatus comprising a tubular body member having a seat at the end thereof, a valve adapted to bear against 70 the said seat, a plurality of angularly placed blades secured to the said valve and fitting movably within the said tubular body member, an angular vane comprising wings set 75 at the same angle as the angle between the said blades, one of the said wings being pivotally connected to one of the said blades adjacent one end thereof, and both of said wings being recessed at their opposite ends in the angular portions thereof, so that said 80 vane lies in the space between two of the said blades, a lever pivotally mounted in the same blade in which the said vane is pivotally connected, the said lever extending into and through the recess in the wings of the 85 said vane and also through a recess in the blade adjacent the one in which the vane is pivotally connected, and a cup member connected to the said lever and lying within the space between the blades adjacent that in 90 which the said vane is placed, the said cup and lever coacting with the said vane so that the pressure exerted by a medium flowing through the said body member causes a part of the said vane to bear against a portion of the said tubular body member to maintain 95 the valve in an open position.

Signed by me this 29th day of June, 1918.
